PORTRABLE STOVE

Claes Vilhelm Allander, Stockholm, Sweden, assignor to
Aktiebolaget Optimus, Flack, Upplands Vasby, Sweden

Filed July 30, 1973, Ser. No. 384,003

Claims priority, application Sweden Feb. 2, 1973

Term of patent 3½ years

Int. Cl. D7—02

U.S. Cl. D7—107

FIG. 1.

FIG. 2

FIG. 3

FIG. 4

FIG. 5FIG. 6FIG. 7FIG. 1 is a three-quarter perspective front view of a portable stove, showing my new design;

FIG. 2 is a three-quarter perspective front view of only the portable stove stand of FIG. 1 with the burner apparatus removed;

FIG. 3 is a three-quarter perspective rear view of the stand of FIG. 2;

FIG. 4 is a bottom perspective view of the underside of the stand of FIG. 2.

FIG. 5 is a three-quarter perspective front view of the burner alone shown mounted in FIG. 1;

FIG. 6 shows a three-quarter perspective rear view of the burner of FIG. 5; and

FIG. 7 is a bottom perspective view of the burner of FIG. 5.

The stove base and burner apparatus have been shown separately in order to clearly disclose the complete ap-

pearance and details of the configuration of the claimed design.

I claim:

The ornamental design for a portable stove, as shown and described:
